United States Patent Office

Des. 228,412

Patented Sept. 18, 1973

228,412

STAMP DISPENSER

William Macowski, Caldwell, N.J., assignor to Ketcham
& McDougall, Inc., Roseland, N.J.

Filed May 19, 1972, Ser. No. 255,314

Term of patent 14 years

Int. Cl. D19—02

U.S. Cl. D52—2 C

FIG. 1

FIG. 2

FIG. 3

FIG. 4

FIG. 5

FIG. 1 is a rear perspective view of a stamp dispenser embodying my new design;

FIG. 2 is a plan view thereof;

FIG. 3 is a side view thereof;

FIG. 4 is a rear view thereof; and

FIG. 5 is a front view thereof.

I claim:

The ornamental design for a stamp dispenser, as shown.
